UNITED STATES PATENT OFFICE.

JAMES FRANKLIN BROWN, OF CINCINNATI, OHIO.

SALES CHART.

Application filed April 22, 1927. Serial No. 185,798.

It is the object of my invention to provide novel means to enable a customer to select goods to be ordered and to fill an order slip held in association with designations of the goods on sale, and so arranged as to remind the customer of goods desired.

It is the object of my invention further to provide a chart comprising a foldable strip, having thereon a representation of a store and the designation of goods to be found in the store, and a pad-holder depending therefrom upon which the designation of goods on the strip may be written by the customer while viewing said designations, and, further, to so construct and arrange the parts of the device as to form a package of the same for permitting the same to be forwarded to the customer by messenger, in the mail, or by other desirable carrying means.

In carrying out my invention, the store supplies my improved devices to its customers, instanced as householders, so that the householder has before her in convenient arrangement designations of the goods sold by the store, and a pad in association therewith, so that she may write on the uppermost slip in the pad the names and quantities of goods desired, and so that she is reminded of goods desired by perusal of the chart in association with the pad. The store is exemplified as a grocery store, but is not limited to a store for the sale of such character of merchandise. The chart comprises a main section, from which wings extend laterally having thereon the designations of goods sold by the store, which designations may be pictorial or literal, and from which a section depends having on it the order pad.

My improved device is shown in the accompanying drawings, in which:

Fig. 1 is a rear elevation of my improved device in spread form, and partly broken away.

Fig. 2 is a front elevation of the same, partly broken away.

Fig. 3 is a front elevation of my improved device, partly broken away, with the side panels of the depicting sales chart in folded relation.

Fig. 4 is a perspective view of my improved device in closed relation ready for carriage.

Fig. 5 is a side elevation of the same, partly in longitudinal section on the line 5—5 of Fig. 4.

Fig. 6 is a cross-section of the same, taken in the plane of the line 6—6 of Fig. 5; and,

Fig. 7 is an enlarged detail of the same, taken on the line 7—7 of Fig. 3.

My improved device comprises a transverse strip 11, of flexible material, and a depending strip 12 preferably integral therewith and arranged to be folded with relation thereto along a score 13, shown in the line with the lower edge of the transverse strip. There is depiction of a store, exemplified as a grocery store, on the transverse strip, preferably on the respective faces thereof.

The store front is depicted in Fig. 1 on the outside or rear face of the transverse strip, and an interior arrangement of the store is depicted in Fig. 2 on the inside or front face of the transverse strip. An awning 14 is shown extending across the store front. The store entrance is depicted in the middle portion of the rear face of the transverse strip, the doors 15 thereof being depicted on the rear face of a main panel 16 of the transverse strip. The doors have designations 17 thereon of goods sold by the store.

Lateral wings 18, 19, extend from the main panel 16, and are hinged thereto by the scores 20, which are shown in line with the side edges of the depending strip 12.

The respective wings are also preferably arranged in panels 21, foldable with relation to each other, as long the scores 22, formed in said wings. The said panels are foldable one upon the other and upon the front face of the main panel, being the face shown in Fig. 2.

The rear faces of said foldable panels have the show windows of the store depicted thereon. These show windows are arranged in sections, each of which has designations 25 thereon of goods which may be bought in the store. The goods are arranged on shelving 26.

The front face of the main panel has designations 27 thereon of goods sold by the store. The front faces of the foldable panels 21 have shelving 28 depicted thereon as well as designations 29 of goods which may be bought in the store.

The designations may be pictorial, as shown at 31, or literal, as shown at 32, and are to remind the user of the device of the goods which are sold in the store and of the goods which the householder who uses the device may be in need of. The compartments

in the shelving may have headings 33 to show the general characters of goods in the respective compartments.

The depending strip 12 is provided with means whereby to secure thereto a pad 35, the pad being an order pad comprising order slips 36 having a backing 37, which is relatively stiff, as of thin card board, and a securing part 38 of similar material in rear of the backing. The securing part comprises a tongue 39, and has shoulders 40 at the respective sides of the base of the tongue.

The securing part is provided with a reversely bent end 41 having a forward downwardly extending portion 42 received about the upper ends of the slips. The slips and backing sheet and securing means are secured together, as by suitable rivets passing therethrough, at their upper ends for forming a head 43 of the pad. The order slips have perforations 44 between their body portions and said head, so that the slips may be readily removed when the orders of the customer have been written thereon for transmission to the store.

The depending strip comprises a pad-holding panel 45 having transverse slits 46, 47, therethrough, through which the tongue 39 is received for securing the pad to the pad-holding panel. The end of the tongue is passed rearwardly through the upper slit 46 and then forwardly through the lower slit 47 and is moved through said slits until the shoulders 40 strike the end walls of the slit 46, which positions the pad with relation to the pad-holding panel. The order pad is arranged at the inner or front face of the pad-holding panel. The outer or rear face of the pad-holding panel is provided with an addressing space 48, on which the name and address of the customer may appear.

The depending strip is also provided with a securing panel 51 provided with a tongue 52.

The pad-holding panel and the securing panel are arranged to be folded about the pad and the folded panels of the transverse strip. The depending strip is provided with a transverse score 53 spaced from the transverse score 13 to form an end fold 54 at one end of the package formed by my improved device when in closed relation. The depending strip is also provided with transverse scores 55, 56, for forming an end fold 57 between them at the other end of the package formed by my improved device.

The pad-holding panel is provided with side wings 61, scores 62 being located between said pad-holding panel and said side wings for ready folding of the latter. The side wings are also provided with scores 63, adjacent to the scores 62, for forming side folds 64 at the sides of the package formed by my improved device in packaged relation, the outer ends of the side wings forming side panels received upon the rear face of the main

panel 16 when the device is in folded relation.

These side panels are provided with slits 65, which are arranged to register with each other endwise when the side panels are folded upon the rear face of the main panel, and the main panel is provided with a slit 66 in registry with the slits 65. When the side wings are so folded, the tongue 52 is arranged to be received through the slits 65 and the slit 66 for arranging my improved device in closed packaged relation.

A clasp 71 is secured to the upper end of the pad-holding panel 45. It is formed of spring metal and comprises tongues 72, 73, connected by a transverse web, one of the tongues being secured to the inner face of the pad-holding panel, as by means of an eyelet 75. The order pad is arranged to be received between these tongues, the lower end of the tongue 73 being provided with a ridge 76 received under the forward down-turned flange 42 of the securing strip of the order pad.

Order pads may be releasably slipped into this clamp, and when the order slips thereof have been used, the head of the order pad may be slipped out of the clamp and a new order pad substituted therefor. The clamp has tongues 77 projecting therefrom to form a clamp for a pencil 78 received in the space 79 between the head of the order pad and the panels of the order chart, the folded arrangement of these panels being shown in Figs. 5 and 6.

A retaining clip 81, shown of arrow form, is pivoted on a pivot pin 82 to the tongue 73 of the clamp for the order pad. This retaining piece may be arranged lengthwise of the head of the order pad, so that the panels of the sales chart may be spread, or said retaining piece may be swung on its pivot so as to be arranged lengthwise upon the folded panels of the sales chart, for holding said panels in folded relation, as shown in Fig. 3.

The sales chart is arranged to have its panels folded one upon the other and upon the main panel, and the order pad is arranged to be secured to the pad-securing panel, and the latter panel swung reversely so that the face of the order pad is presented to the folded panels, the end fold 54 being at one end of the space between the main panel and the pad-holding panel.

The side wings 61 are thereupon folded upon the outside or rear face 27 of the main panel, with the side folds 64 closing the sides of the space between the main panel and the pad-holding panel. This arranges the slits 65 in registry with each other and with the slit 66.

The depending strip is thereupon further folded so that its end fold 57 closes the other end of the space between the main panel and the pad-holding panel, and the tongue 52 is passed through the slits 65, 66, the end of the

tongue being located between the main panel and the adjoining folded panel of the sales chart.

5 A sealing strip 83 may thereupon be pasted across the slit 84 between the proximate edges of the side panels, and upon the adjoining margins of the wings 61, which sealing strip may be a postage stamp, if desired, for securing my improved device together in folded 10 relation. Said securing strip is however not essential, as the device will stay in folded relation without such strip.

The addressing space 48 is exposed at the outer face of the main panel and of the package for receiving the address of the customer 15 to whom my improved device is to be delivered.

The customer may attach my improved device to a wall adjacent to the telephone, using 20 a hole 85 in the main panel for hanging the device on a nail or hook. The strip 12 is arranged in depending relation and, if desired, that portion thereof below the score 55 may be removed by severing the same along said 25 score.

The side panels of the sales chart may be arranged in laterally extending relation, so as to expose the designations at the front faces of the main panel and the side panels, and the 30 side panels are readily reversible by swinging the same on the scores 20, for exposing the designations at the rear faces of the same, to the view of the person who is using the order pad for writing out an order.

35 The designations, both pictorial and literal,

are reminders to the customer of the goods sold by the store and of the possible requirements or desires of the customer.

When the order has been written on the slip, 40 the side panels may again be folded upon each other and upon the main panel, and the retaining clip swung across the same to hold the same in place, so that the device occupies little space when not in use. If desired, the side wings 61 may also be removed along the 45 scores 62, after the device has been delivered to the customer.

Having thus fully described my invention, what I claim as new, and desire to secure by Letters Patent, is:

50 In a device of the character described, the combination of a transverse strip and a depending strip arranged at right angles to each other and each comprising foldable panels extending in the same direction when said device is open, said panels of said transverse strip foldable upon each other, said depending strip foldable endwise about said folded transverse strip with the panels of said depending strip encompassing the side edges of 55 said folded panels of said transverse strip, said panels of said depending strip and a panel of said main strip thereunder when in folded relation provided with registering slits, and said depending strip provided with 60 a tongue received in said slits for holding said folded panels in folded relation.

65 In testimony whereof, I have hereunto signed my name.

JAMES FRANKLIN BROWN.
